UNITED STATES PATENT OFFICE.

JOSEPH E. BERGFALK AND SVEN A. BERGFALK, OF NEW YORK, N. Y.

METAL WEATHER STRIP.

Application filed October 9, 1925. Serial No. 61,426.

This invention relates to improvements in metal weather strips.

The object of this invention is to produce a metal weather strip which has wide limits 5 of adjustment so as to fit and compensate for relatively wide variations in the spaces between the adjacent surfaces of the sash and frame due to variation in the widths of sashes in relation to the inner surfaces of the frames 10 and still produce a tight weather proof joint between such adjacent surfaces.

Another object of the invention is to utilize a construction of weather strip which when applied on opposite sides of a sash will 15 provide a pair of firm, though cushioned, tracks for the sash and will prevent any rattling of the sash during operation by maintaining close and firm though resilient contact at opposite edges between the sash and 20 frame, even though the space between the sash and groove surface is relatively large.

Another object of the invention is to produce a metal weather strip which will be extremely simple and efficient in its function of 25 weather proofing sliding sashes and which will facilitate the assembly of the sashes and frame.

With these and other objects in view, the invention comprises the combination of members 30 and arrangement of parts so combined as to co-act and cooperate with each other in the performance of the functions and the accomplishment of the results herein contemplated and comprises in one of its adaptations the species or preferred form illustrated in the accompanying drawings, in which:—

Fig. 1 is a fragmentary horizontal cross section through opposite stiles of the sash and 40 frame on which our weather strip is applied;

Fig. 2 is a view, in perspective, of one member of a pair of metal weather strips embodying our invention; and

Fig. 3 is a view, in perspective, of a cushioning element embodying our invention.

Referring now to Figs. 1 to 3 of these drawings which illustrate a preferred embodiment of our invention, 1 indicates the opposite pulley-stile members or jambs of a conventional window frame or casing having sash grooves 2 formed between molding 3 and parting beads 4 in which grooves a sash 5 having stiles 6 is mounted to slide vertically.

55 Sashes of varying widths will obviously cause the spaces at opposite sides thereof be-

tween the edges of the stile 6 and the surfaces 7 of the pulley-stile members 1 to vary, it being apparent that the narrower the sash the wider will be such spaces between the edges thereof 60 and the surfaces of the jamb and in accordance with our invention, we provide weather strips which not only span spaces of varying widths and provide air-tight and water-tight joints between such sash and frames but also 65 prevents excessive side-wise movement of the sashes which would cause a rattling during a raising and lowering operation and, furthermore, provides a pair of smooth flat and firmly supported, though cushioned, tracks 70 for the sash to slide upon, thus facilitating the operation of raising and lowering the sash. This is accomplished by the use of a weather strip which is extremely simple in construction and may be manufactured at a 75 very low cost.

In the construction illustrated, we provide the edges of the sash stiles 6 intermediate the outer and inner side faces with grooves 8 and, as illustrated, we insert in each of the said 80 grooves 2 between the edges of said stiles 6 and the face of the pulley stile 1, a metal weather strip 9. Each strip has one marginal edge anchored to the frame or pulley

85 stile at one side of the sash groove, an opposite marginal edge freely movable in a groove in said pulley stile at the opposite side of the sash groove, and an intermediate portion formed into a loop 12 which engages the groove 8 in the sash, a sash-contacting track 90 portion between said loop and the free marginal edge and a space-bridging portion between said loop and said anchored margin.

As shown, the anchored marginal edge has an attaching flange 10 which extends beneath 95 the molding 3 at one side of the sash groove

2 and is there anchored to the pulley stile 1 by nails 10^a while the opposite marginal edge terminates in a freely movable flange 15 bent at a right angle from the body of the strip and fitting in a groove or kerf 4^b formed

at the opposite side of the sash groove between the parting bead 4 and the wall 1^a of a groove 4^a within which the parting bead 4 seats. The intermediate portion 11 extends 100

the entire width of the groove 2 and is provided with said intermediate groove-engaging loop-portion 12 which divides said intermediate portion to produce a space-bridging portion 13 at one side of said loop and a 105

sash-contacting track portion 14 at the opposite side thereof, which latter portion 110

merges with said flange 15 which is movable in said adjusting groove 4^b.

This construction of weather strip when properly supported will close the spaces between the surfaces of the jamb 7 and the edges of the sash to form water-tight and air-tight joints and the movement of the free-edged flange 15 in the groove 16 will enable adjustability of the strip which may be utilized to provide such a weather-proof joint across spaces of relatively wide variation due to variations in the widths of sash and frames. It will be clear that the bridge portion 13 is flexible and will swing about the joint 16 between the said attaching flange 10, thus, in effect, providing a hinged joint which will allow substantially free movement to accommodate itself, as aforesaid, to widths of varying spaces.

While a resilient construction of type so far described is desirable to procure a tight-joint over widely varying spaces, as aforesaid, it is ineffective to prevent lateral movement of the sash which sometimes causes rattling and will not form a properly supported and cushioned track for the sash. In order, therefore, to prevent such rattling, to reinforce and cushion the contacting-track portion 14 and cause it to hug the sash so as to provide a properly supported though resilient guiding member for the sash, we insert within the space between the body portion 11 of the weather strip and the surface 7 of the groove, a resilient cushioning and compensating element 17 preferably comprising, as shown in Figs. 1 to 3 an independent folded strip of metal bent intermediate its edges to provide free flanges 18 and 19 at opposite sides of the bend 20. This cushioning compensating element may thus be readily and easily inserted between the surfaces of the groove and the body portion of the weather strip and not only compensates for varying sizes of spaces but will resiliently press the track portion 14 into firm contact with the edge of the sash so as to effectively prevent the same from rattling, thus converting said freely movable contacting portion of the flexible weather strip into a spring-pressed portion and producing firm though resilient guiding members for the opposite edges of the sash.

It will be seen that the use of an independent cushioning strip will permit ready insertion in a groove the edges of which are closed so as to avoid open grooves which gather dirt and also will avoid all unnecessary bending or doubling of the weather strip proper.

Having described our invention, we claim:

1. The combination with a window frame having sash grooves and a sash mounted within said grooves and having grooves at its op-

posite side edges of weather strips arranged within said grooves, each having a connection at one marginal edge to one side of one of said grooves and having the opposite edge free, the said strip being bent intermediate its edges to form a loop extending into said groove in the sash and having a space-spanning portion between said loop and said connected marginal edge and a contacting track-portion between said loop and the free edge, said free edge having a freely movable flange bent at a right angle to the body of the strip extending in a direction opposite to the said loop and in a plane parallel therewith, and means for resiliently forcing said contacting track portion into engagement with the edge of the sash.

2. The combination with a window frame having sash grooves and a sash mounted within said grooves and having grooves at its opposite side edges of weather strips arranged within said grooves, each having a connection at one marginal edge to one side of one of said grooves and having the opposite edge free, the said strip being bent intermediate its edges to form a loop extending into said groove in the sash and having a space-spanning portion between said loop and said connected marginal edge and a contacting track-portion between said loop and the free edge, said free edge having a freely movable flange bent at a right angle to the body of the strip extending in a direction opposite to the said loop and in a plane parallel therewith, and an independent resilient element arranged in back of said track portion to force the same into engagement with the edge of the sash.

3. The combination with a window frame having sash grooves and a sash mounted within said grooves and having grooves at its opposite side edges of weather strips arranged within said grooves, each having a connection at one marginal edge to one side of one of said grooves and having the opposite edge free, the said strip being bent intermediate its edges to form a loop extending into said groove in the sash and having a space-spanning portion between said loop and said connected marginal edge and a contacting track-portion between said loop and the free edge, said free edge having a freely movable flange bent at a right angle to the body of the strip extending in a direction opposite to the said loop and in a plane parallel therewith, and an independent V-shaped resilient strip arranged in back of said track portion to force the same into engagement with the edge of the sash.

In witness whereof, we have signed our names to the foregoing specification.

JOSEPH E. BERGFALK.
